CLAIM

The ornamental design for a solar cell, as shown and described.

DESCRIPTION

This application is also related to U.S. patent application Ser. No. 29/476,182, filed Dec. 11, 2013, now U.S. Pat. No. D765,590, and its divisional U.S. application Ser. No. 29/566,655, filed Jun. 1, 2016 now U.S. Pat. No. D846,489. FIG. 1 is a top perspective view that illustrates the solar cell showing our new design;

FIG. 2 is a top plan view thereof;

FIG. 3 is a cross-sectional view through the 3-3 plane shown in FIG. 2;

FIG. 4 is a cross-sectional view through the 4-4 plane section in FIG. 2;

FIG. 5 is a cross-sectional view through the 5-5 plane shown in FIG. 2;

FIG. 6 is a cross-sectional view through the 6-6 plane shown in FIG. 2;

FIG. 7 is a cross-sectional view through the 7-7 plane shown in FIG. 2;

FIG. 8 is a cross-sectional view through the 8-8 plane shown in FIG. 2;

FIG. 9 is a cross-sectional view through the 9-9 plane shown in FIG. 2;

FIG. 10 is a cross-sectional view through the 10-10 plane shown in FIG. 2;

FIG. 11 is a cross-sectional view through the 11-11 plane shown in FIG. 2;

FIG. 12 is a bottom plan view thereof;

FIG. 13 is a front side elevation view thereof;

FIG. 14 is a left side elevation view thereof;

FIG. 15 is a front side elevation view thereof;

FIG. 16 is a right side elevation view thereof; and,

FIG. 17 is a top plan view of the solar cell in a second embodiment.
